UNITED STATES PATENT OFFICE.

LOUIS WOJIDKOW, OF BROOKLYN, NEW YORK.

DESIGN FOR A TEA-KETTLE.

SPECIFICATION forming part of Design No. 27,943, dated December 7, 1897.

Application filed October 20, 1897. Serial No. 655,861. Term of patent 3½ years.

To all whom it may concern:

Be it known that I, LOUIS WOJIDKOW, a citizen of the United States, residing at Brooklyn, county of Kings, and State of New York, 5 have invented and produced a new and original Design for Tea-Kettles, of which the following is a specification, reference being had to the accompanying drawings, forming part thereof.

10 Figure 1 is a side elevation of a teakettle, showing my new design; and Fig. 2 is a plan view of the same.

As shown in the drawings, the leading or material feature of my design consists of a series of convexed upwardly-extending panels 15 formed on the main body of the kettle, while similarly-convexed panels are formed on the upper part of the kettle, so as to radiate from the central part.

20 The body A of the kettle is provided with convexed panels b, which extend upwardly and radiate from the scalloped base C, while above the lower part of the kettle, at the top

thereof, is formed a series of convexed radiating panels d, said panels radiating from a scalloped flange or rim E. Above the latter is arranged the dome-shaped corrugated lid F. The larger portion of the body, at the point where it joins the top of the same, is provided with a beaded border h. The handle 30 consists of a curved grip I and volute side bars J, which rise from the top of the body of the kettle.

Having described my invention, what I claim as new, and desire to secure by Letters Patent, is—

The design for a tea-kettle, substantially as herein shown and described.

In testimony that I claim the foregoing as my invention I have signed my name in presence of two subscribing witnesses.

LOUIS WOJIDKOW.
